OPTICAL OBJECTIVE

Albert Baab, Bad Kreuznach, Rhineland, Germany, assignor to Jos. Schneider & Co., Optische Werke, Kreuznach, Rhineland, Germany, a corporation of Germany

Filed Mar. 29, 1960, Ser. No. 59,933

Term of patent 14 years

Claims priority, application Germany Dec. 16, 1959

(Cl. D57—1)

FIG.1

FIG.2

FIG.3

FIG. 1 is a perspective view of one side of an optical objective showing my new design;

FIG. 2 is a perspective view of the opposite side of the objective; and

FIG. 3 is an end view thereof.

The bottom of the objective, not shown, is substantially flat except for the conventional central projecting cylinder.

The dominant features of my design reside in the portions shown in full lines.

I claim:

The ornamental design for an optical objective, as shown and described.
